UNITED STATES PATENT OFFICE.

WILLIAM A. HANCE, OF FREEPORT, ILLINOIS, ASSIGNOR TO THE WARNER MANUFACTURING COMPANY, OF ILLINOIS.

DAMPER.

SPECIFICATION forming part of Letters Patent No. 403,467, dated May 14, 1889.

Application filed February 19, 1889. Serial No. 300,419. (No model.)

To all whom it may concern:

Be it known that I, WILLIAM A. HANCE, a resident of Freeport, in the county of Stephenson and State of Illinois, have invented 5 certain new and useful Improvements in Dampers; and I do hereby declare the following to be a full, clear, and exact description of the invention, such as will enable others skilled in the art to which it pertains to make 10 and use the same.

My invention relates to stove-pipe dampers, and particularly to combining with the damper-blade a handle that may be detachably secured to the blade after the latter has 15 been inserted in the pipe.

The invention is fully set forth in this specification and the accompanying drawings, wherein—

Figure 1 shows the damper seen from above 20 when in position to cut off the draft in a vertical pipe. Fig. 2 is a section on the line *x x*, Fig. 1. Fig. 3 is an enlarged detail view of a part of the apparatus shown in Fig. 1. Figs. 4, 5, 6, and 7 show modified forms of the 25 external portion of the handle. Figs. 8 and 9 show the blade with handles modified both as to external and internal construction. Fig. 10 is a section on the line *y y*, Fig. 8.

In the drawings, A is a damper-blade provided with a radial groove spanned by bridges C' C'' and terminating in an opening, D. In line with this groove, upon the opposite side of the blade, is a short gudgeon, E, to enter a suitable aperture in the pipe. A handle-shaft, G, enters through an opening in the pipe diametrically opposite to the aperture for the gudgeon E, and with the latter serves as an axis upon which the damper may rotate. The shaft is carried to a suitable distance without the pipe, coiled at H and H', and then carried back nearly to the pipe, where it is coiled about its own main portion to form a yielding shoulder, K, resting against the exterior of the pipe. The inner end of the 40 shaft is bent at right angles to form a short hook, I, for engaging the blade.

To secure the damper in position, the gudgeon E is inserted in its aperture, and the groove is brought into diametrical line with 45 it, the shaft with its hook upward is passed

through the pipe into the groove and advanced to the bridge C', then rotated, turning the hook downward through the opening J, advanced to the bridge C'', and rotated to bring the hook again upward through an aperture, J', when it is again advanced till the shoulder K meets the pipe. The hook will now be at the beginning of the inclined wall of the opening D, as indicated in dotted lines in Fig. 3. If the shaft be now forcibly rotated while the damper is held fast, the hook passes along the incline and draws the shaft inward, the coils at K H H' yielding until it leaves the incline and passes into the space inclosed by the inner edge of the wall of the 60 opening D. When in its continued rotation the hook becomes perpendicular to the blade, it is drawn back into a notch, M, by the elastic force of the coils, and the damper is ready 65 for use. The damper may be disengaged either 70 by great torsional force applied while the blade is held fast or by pressing the shaft inward and then reversing the motions of insertion.

The form of the external springs may be 75 varied, as indicated in Figs. 4, 5, 6, and 7. As shown in Figs. 4 and 5, the coils H H' are omitted, and a single coil of helical form is used next the pipe. As shown in Fig. 5, the coil is replaced by a spring formed by carrying the 80 wire back and forth in its own plane, and in Fig. 6 both forms are employed.

The remaining figures illustrate single-wire constructions, where the shaft is double and forms at its inner end a loop, O, that passes 85 over a hook, P, upon the plate or blade. In these cases the loop is passed over the hook by pressing inward upon the handle, and is drawn back beneath it by the recoil of the springs outside the pipe, which act in the same 90 manner as in the other cases. It is evident that when the loop is employed no rotation is required to engage or disengage the loop and hook.

What I claim is—

1. In a damper, the combination, with a blade having a recess for the bent end of a handle-shaft or spindle, of a handle-shaft having at its inner end a lateral bend lying in said recess and having its outer end bent upon it. 100

self, forming a spring pressing the edge of the blade, whereby the force of the spring tending to withdraw the shaft longitudinally presses the bent end into the recess and maintains the engagement of the handle with the blade.

2. The combination, with a blade having a radial passage into which a handle-shaft may be thrust and at the inner end of the passage a recess adapted to receive the laterally-bent end of such shaft, of a handle-shaft provided at its inner end with a bend or hook and having its outer end returned upon itself in the form of a spring pressing the edge of the blade, substantially as set forth.

3. The combination, with the blade having the groove, the bridges spanning the same, the openings, and the recess for the hooked end of the handle-shaft, of the handle-shaft having the hooked inner end lying in said

recess and the integrally-formed spring pressing the edge of the blade, substantially as set forth.

4. The combination, with the blade A, having the opening D, with inclined walls recessed at M, the radial groove spanned by the bridges C C' C'', and the openings J J', of the handle-shaft G, lying in said groove, and having at its inner end the bend or hook I and at its outer end the integrally-formed spring-handle terminating in a coil about the shaft in close proximity to the edge of the blade, substantially as set forth.

In testimony whereof I have signed this specification in the presence of two subscribing witnesses.

WILLIAM A. HANCE.
